UNITED STATES PATENT OFFICE.

THOMAS B. DE FOREST, OF BIRMINGHAM, CONNECTICUT.

SKIRT.

Specification of Letters Patent No. 31,876, dated April 2, 1861.

To all whom it may concern:

Be it known that I, THOMAS B. DE FOREST, of Birmingham, county of New Haven, in the State of Connecticut, have invented certain new and useful Improvements in Hoop-Skirts; and I do hereby declare that the following is a full and exact description thereof, reference being had to the accompanying drawings, making part of this application.

10 Previous to my invention the following prominent disadvantageous features have existed in hoop skirts as made and worn:—

15 1stly. The liability of entanglement of the feet with the lower hoops in walking. This obstacle to the comfort and safety of the wearer is proverbial.

20 2ndly. The inconveniences arising from having to put on and take off the hoop over the head have been a great source of annoyance frequently to ladies in dressing.

25 3rdly. The speedy derangement of the lower hoops and their becoming very soon dirty has rendered the whole skirt very soon unfit for wear, and thus render it necessary to renew the whole skirt at considerable expense.

30 4thly. The tendency of the lower hoop to remain hitched or bent up behind after sitting has been a great annoyance.

35 My present invention has for its object to overcome all these disadvantages and thus render the hoop skirt a more desirable, less, dangerous and more economical article of dress; and to these ends my invention consists in forming the skirt with an opening, or open space in front (and also behind if necessary) at the base of the skirt to allow the free swing or motion of the wearer's feet, without any liability of entanglement in 40 walking, as will be hereinafter fully described. And my invention consists further, in making the skirt in such manner that it can be opened and closed as hereinafter explained, so that the skirt can be put on and

45 taken off without passing it over the head as will be hereinafter described. And my invention consists further in making the lower portion of the skirt separate and detachable from the other portion, for the purpose of renewing the former as will be hereinafter described.

50 And my invention consists further in a peculiar method of forming the skirt, by bending the lower hoop, or hoops up the front as will be presently described so that the lower hoop will always have a tendency to spring downward be-

hind, into its proper position as will be fully described hereinafter.

In the accompanying drawings forming part of this specification Figure 1 is a perspective view and Figs. 2, 3, 4 and 5 are each side elevations of a hoop skirt, the several views illustrating the several features of my invention—and to be particularly alluded to hereinafter.

65 The same characters indicates the same part in the different views.

In Fig. 1 are embraced the first, second and fourth features of my improvements; in Fig. 2 are seen the first, second and third features; in Fig. 3 is seen the first only; in Fig. 4 is illustrated a modification of first feature, and at Fig. 5 another modification of the same.

70 *a* are the hoops, and *b* the vertical bands or supporting strips, the construction of each of which parts and the method of connecting the two forming no part of my invention are shown in the most approved fashion.

75 *A* is the open space in front for the feet to pass in and *B* the space behind.

80 The skirt illustrated at Fig. 5 has an open space formed behind as well as before, while the other figures show only the space before.

85 *C* is the waist band which is made in the usual way.

90 At Fig. 3 the feet opening, or space *A* (in front) is formed by bending the bottom hoop *a'* upward, crossing it at 5 and uniting or securing its two ends at 1, 2, to the fourth hoop *a⁴*, the second hoop *a²* being stopped off at 3, 4 and its ends there united to hoop *a'*, as illustrated. In the modification of this first feature of my invention 95 shown at Fig. 4, the lower hoop *a'* is bent up in the same way but is not crossed as in Fig. 3, but simply united at a single point 1, the hoop *a²* having its two ends united to hoop *a'* at the points 2, 3.

100 In Fig. 5 the skirt appears as made with an open space behind as well as one before, that behind however, not being so large as the one before.

105 *g* and *h*, (see Fig. 1,) are two flaps, or overlapping pieces of cloth, or other suitable material, one provided with buttons, *o*, the other with button holes, by which the skirt is fastened or closed around the person of the wearer, (the waist bands *C* being fastened as usual). At Fig. 2 another mode 110 of applying this second feature of my inven-

tion is shown, consisting in lacing the skirt together down the front with a cord *i*, passing through eyelet holes; in this figure the skirt is not shown as capable of being 5 opened or separated all the way down (as in Fig. 1,) but only down to the "detachable" lower portion. This latter is formed of four continuous or unbroken circles or hoops with the vertical strips *b*, the whole 10 separate and distinct from the other part of the skirt and, attachable thereto by buttons *c* or in any other suitable manner. In the 15 employment of this feature of my invention it may be deemed advisable to have the skirt open only down to the removable bottom piece, as shown at Fig. 2, since the wearer can readily step into the lower portion and then close the other part around her, and the making both portions to open would 20 involve more expense and might render the skirt less effective in keeping the dress distended properly.

At Fig. 1 it will be seen that the lowest hoop *a'* is bent up to form the open space 25 A, crossing at the point 1 and continuing in curved line up the front of the skirt, crosses again at the point 2, and then has its ends united to the waist band. By thus extending the said hoop *a'* up as shown the lowest 30 hoop is converted into a strong spring, the tendency of which is to constantly descend at the hindmost point, which tendency always pulls and keeps the other hoops down behind, in their proper position, while the 35 same principle of construction involves a tendency to brace the front of the skirt vertical and keep all the hoops apart and "down in front." It will then be understood that by this fourth feature of my invention the skirt is rendered much more 40 perfect and desirable, the hoops being always kept apart and pulled down in their proper places, while at the same time the whole skirt yields readily in sitting, and 45 is exceedingly comfortable and it will be understood that this spring may be formed by bending up more than one hoop as shown. The removable lower portion may be made of more or less hoops than shown 50 as may be deemed expedient. It will be seen that by making the lower portion de-

tachable as shown and described it can be readily renewed when its hoops become broken or dirty—the other portion always being capable of remaining in a good condition a longer time than the bottom portion will last.

It will be seen that the several features of my invention though they constitute the proper subject matter of this one application, are each capable of application independently without being deprived of their advantages.

I do not wish to be understood as limiting the first part of my invention to the formation of the open space before only, or behind only, nor to the combination of both, but wish to cover the formation of the open space in either or both places as may be deemed expedient. Neither do I wish to 65 limit myself to the precise forms or proportions of detail construction shown; but

Having explained the construction and operation of each of the several features of my invention as I have successfully practiced them, what I claim as new and desire to secure by Letters Patent is—

1. Forming an open space, or open spaces, to accommodate the feet in walking substantially as hereinbefore set forth. 80

2. Making the skirt to open in front or behind, wholly or partially by continuing the bottom hook up to the waist-band, or other desired point, and connecting thereto the ends of the other hoops as hereinbefore 85 described.

3. Making the lower portion of the skirt detachable, or removable from the rest at, or near the termination of the open space substantially as and for the purposes de- 90 scribed.

4. Forming the lower hoop or hoops into a spring, by bending up, to operate as, and for the purpose hereinbefore described.

In testimony whereof I have hereunto set 95 my hand and affixed my seal this 25th day of February, 1861.
